SPRINKLER

Morris D. Morgan, Spokane, Wash.

Application May 12, 1944, Serial No. 535,275

4 Claims. (CL. 299—67)

1

This invention relates to a sprinkler and, more particularly, to a rotary spraying device useful in sprinkling lawns and gardens.

It is my observation from a wide experience with sprinkling equipment, as now available, that there are several disadvantages which detract from the use of such equipment. I have noted that the majority of the spray producing devices make no fully advantageous use of the power available to break up the water into fog-like particles. Another criticism of the present equipment lies in the improper distribution of the spray over an area being sprinkled, which is partly due to the necessity of so employing the available power to effect highspeed rotation in such a manner that there is no lateral water throw of any consequence. Of the sprinklers available, in that type which I designate as rotary reaction or jet propulsion type, wherein the discharge of water from a non-axial outlet results in the rotary movement of the spray head, the lateral and centrifugal components of force cross each other out, with the result that the spray head moves but the water, in fairly large droplets, falls substantially at the point of ejection.

Having in mind the defects of the prior art, it is an important object of my invention to provide, in a sprinkler, improved spray formation to insure an even deposit of fine spray over the area being sprayed.

Another object of the invention is the provision, in a sprinkler, of rotary means other than reaction propulsion to enhance fog formation.

A still further object of the invention lies in the improvement of fluid dispersion and distribution over an area relatively larger than has heretofore been possible by similar equipment.

These and other objects, as will be more apparent hereafter, are accomplished by a mechanism which includes a base to rest on the ground. A casing supported on the base, has a turbine chamber, in which is mounted a vaned rotor against the vanes of which water introduced through a non-axial passage impinges to carry the rotor around. In this preferred form of my invention the shaft of the rotor is tubular and has openings by which water may escape from the chamber and pass out along the axis of the rotor through a portion of the shaft which extends externally of the chamber. Connected to the external portion of the rotor shaft and laterally thereof is a cross head, which may include two or more arms having spray nozzles, through which escaping fluid is discharged. Ground anchor means is provided upon the base for positively positioning the same during use. Hose coupling means is associated with the chamber inlet passage so that a water hose or pipe may be connected with facility.

2

This preferred form of my invention as outlined above, together with certain modifications in detail, is illustrated in the accompanying drawings, in which:

- Figure 1 is a view in elevation of my sprinkler;
 Figure 2 is an enlarged vertical sectional view of the operating mechanism of my sprinkler, with portions omitted for convenience of illustration;
 10 Figure 3 is a lateral sectional view taken on line 3—3 of Figure 1;
 Figure 4 is a fragmentary vertical sectional view of the lower end of the rotor shaft;
 Figure 5 is a bottom plan view of a vane securing collar used in my rotor;
 Figure 6 is a fragmentary perspective view of a discharge nozzle; and
 Figure 7 is an elevational view of a modified form of rotor that may be used in my sprinkler.
 20 Referring to the drawings, the numeral 10 designates a supporting base for the casing 12 which provides the interior chamber 14. On the bottom of the base in boss 16, I threadably mount the anchor pin 18 which may be inserted into the ground G to anchor securely in place the sprinkler during use.
 An orifice 20 in the wall of the casing 12 permits the introduction of fluid thereto and the non-axial conduit 22 directs fluid to the cylinder in a chordal manner. A female coupling swivel 24 cooperates with the male member 26 of a hose 28 whereby water is supplied to the sprinkler. In the lower portion of the chamber 14, axial thereof, I mount the adjustable bearing pin 30 having the threaded shank 32, whereby its shoulder portion 34 may be raised or lowered as desired.
 The chamber 14 is closed by cover 36 which has a central bearing sleeve 38 aligned with the axis of pin 30.
 40 The rotor comprises the tube 40, having lower openings 42 and a closed bottom 44, provided with a suitable opening to engage the pin 30. Between collars 46 and 48, which are secured by means of screws 50, is mounted a plurality of blades 52, which stand substantially radial of the tube 40. As shown in detail in Figures 2 and 5, the vanes 52 may have ears 54, which are engaged in recesses 56 of the collars 48 and 46 to lock the same in place. The tubular shaft 50 extends upwardly through the bearing sleeve 38. The upper collar 48 is closely adjacent to the lower end of the sleeve 38. The top of the collar forms a shoulder facing the sleeve. It is evident that the shoulder portion 34 of the pin 30 can be set to the right elevation to maintain such spacing between the collar 48 and the sleeve 38 as to prevent any substantial endwise movement of the shaft 40.
 50 Upon the upper end of the tube 40 I mount

the T-shaped member 60, from the opposite sides of which extend the hollow distributor arms 62. As shown in Figures 1 and 6, each arm 62 has an outer portion 64 disposed at an angle thereto, on the ends of which are spray nozzles 66.

In Figure 7 the rotor tube 43, having the usual openings 45, is provided with vanes 53 that are curved in a spiral manner. The rotor of Figure 7 may be interchanged with that of Figures 2 and 3, when it is desired to change the rotary characteristics of the turbine mechanism.

In operation, water under pressure is supplied by hose 28 to the passage 22 and is discharged into the chamber 14 through the orifice 20. The water thus enters the chamber in a non-axial direction to impinge upon the vanes 52 of the rotor and produces rotation of the tube 40. The water escapes from the interior of the chamber 14 through openings 42 and passes out of the casing through the external portion of tube 40, from whence it is distributed by the arms 62 to the nozzles 66.

It will be seen that if the arms 62 and their angularly disposed portions 64 are directed radial of the axis of rotation, rotation produced by the turbine mechanism will create centrifugal force in addition to the outward radial flow of the discharging water and that the water will be thrown a considerable distance from the sprinkler while also being broken up by the rotary action. In those cases where the angular portion 64 of the arm 62 is directed in reverse to the direction of rotation, as in a re-action wheel, there will nevertheless be additional centrifugal force produced by the rotor to effect outward throw of the water as it escapes at the ends of the arms through nozzles 66. It is possible by the use of my device to direct the nozzles into the direction of rotation, and, because of the action of the turbine, to produce fog coupled with outward distribution over an area substantially larger than with a re-action wheel of similar size that depends for rotation upon only the escape of the water from the distributor arms.

While I have shown and described particular embodiments of my invention, it will occur to those skilled in the art that various changes and modifications may be made without departing from the invention, and I, therefore, aim in the appended claims to cover all such changes and modifications as fall within the true spirit and scope of my invention.

Having thus described my invention, I claim:

1. A rotary spraying device comprising, a casing including a chamber having a fluid inlet in a wall thereof, a bearing in the top of the casing, a tube in the casing extending through said bearing and having a spray head coupled thereto, spaced collars on said tube, vanes secured by said collars in spaced relation about the tube, the fluid inlet being directed non-axially of the tube whereby to cause fluid entering the chamber to strike said vanes and effect rotation of the tube, and said tube having inlet openings axially spaced from said vanes to receive the spent fluid from the vanes.

2. A rotary spraying device comprising, a casing including a chamber having a fluid inlet in a wall thereof, a bearing sleeve in the top of the casing, a tube in the casing extending through said bearing sleeve and having a spray head coupled thereto, upper and lower collars on said

tube, the upper collar being positioned adjacent to the bearing sleeve in the top of the casing, vanes extending between and secured by said collars in spaced relation about the tube, the fluid inlet being directed non-axially of the tube whereby to cause fluid entering the chamber to strike said vanes and effect rotation of the tube, said tube having inlet openings spaced axially below said vanes to receive the spent fluid from the vanes, and a vertically adjustable bearing for the lower end of said tube in said casing.

3. A rotary spraying device comprising a casing including a chamber having a fluid inlet in a wall thereof, a tube mounted in said chamber for rotation on a vertical axis, said tube having a series of vanes thereon spaced circumferentially about the tube within the casing, said tube having a portion extending through the top of the casing, a spray head on said portion, a bearing sleeve in the top of said casing around said portion of the tube, a bearing shoulder on said tube adjacent to the lower end of said sleeve, a bearing pin mounted in the bottom of said casing, said tube having a bottom aperture slidably and rotatably receiving the pin, the fluid inlet being directed non-axially of the tube to cause fluid entering the chamber to strike said vanes and rotate the tube, and said tube having openings in the wall thereof below the level of the vanes directing spent fluid from the chamber into the tube.

4. A rotary spraying device comprising a casing including a chamber having a fluid inlet in a wall thereof, a tube mounted in said chamber for rotation on a vertical axis, said tube having a series of vanes thereon spaced circumferentially about the tube within the casing, said tube having a portion extending through the top of the casing, a spray head on said portion, a bearing sleeve in the top of said casing around said portion of the tube, a bearing shoulder on said tube adjacent to the lower end of said sleeve, a bearing pin mounted in the bottom of said casing, said tube having a bottom aperture slidably and rotatably receiving the pin, the fluid inlet being directed non-axially of the tube to cause fluid entering the chamber to strike said vanes and rotate the tube, and said tube having openings in the wall thereof below the level of the vanes directing spent fluid from the chamber into the tube.
